UNITED STATES PATENT OFFICE.

CHARLES L. PEIRCE, JR., OF PITTSBURGH, PENNSYLVANIA.

INSULATOR RACK.

Application filed May 27, 1922. Serial No. 564,275.

The invention relates to insulator racks and it has particular relation to racks adapted to support a plurality of insulators in superposed relation.

- 5 Heretofore it has been necessary, in mounting insulator racks of this general character upon a supporting structure or pole, to first remove the insulators carried thereby in order to permit of the insertion of the through bolt 10 through the base portion of the rack for engagement with the supporting structure. This practice has resulted in much inconvenience and the loss of time. Furthermore, in the construction of racks of the type described, it has been customary to form the insulator supporting arms with tenons which were separately riveted in apertures formed in the base member which necessitated much manual labor and the consequent expense.
- 20 One of the objects of the invention is to provide a device, of the character described, in which the various parts may be constructed from stock material and quickly assembled with a minimum of time and labor.
- 25 Another object of the invention is to provide a device, of the class set forth, which may be secured to a supporting structure without removing any of the insulators carried thereby.
- 30 With such objects in view, as well as other advantages which may be incident to the utilization of the improvement, the invention consists in the parts and combinations thereof hereinafter set forth and claimed, with the understanding that the several necessary elements constituting the same may be varied in proportion and arrangement without departing from the nature and scope of the invention.
- 40 In order to make the invention more clearly understood, means are shown in the accompanying drawings for carrying the same into practical effect, without limiting the improvements, in their useful applications, to the particular constructions, which, for the purpose of explanation, are made the subject of illustration.

In the accompanying drawings:—

Fig. 1 is a front elevational view of an insulator rack constructed in accordance with the invention.

Fig. 2 is a vertical sectional view taken on line II—II of Fig. 1.

Fig. 3 is a horizontal sectional view taken on line III—III of Fig. 1.

Fig. 4 is an enlarged horizontal sectional view taken on line IV—IV of Fig. 1 and illustrates a tongue portion disposed in an aperture in a base portion before the retaining lip has been bent into the aperture to prevent the displacement of the tongue portion therefrom.

Fig. 5 is a view similar to Fig. 4 but showing the lip portion bent into the aperture and into engagement with the tongue to prevent the displacement thereof.

Fig. 6 is an enlarged vertical sectional view taken on line VI—VI of Fig. 1 and illustrating the T-shaped tenons or tongue portion of a supporting arm disposed within an aperture in a base member.

Fig. 7 is an enlarged fragmentary view illustrating a tenon slot and retaining lip.

Fig. 8 is a fragmentary front elevational view of an insulator rack and illustrating the transversely extending bridging member in position for securing the rack to a supporting structure or pole.

Fig. 9 is a horizontal sectional view taken on line VIII—VIII of Fig. 8 and showing the bridging member in interlocked engagement with the base members of the rack.

Fig. 10 is a perspective view of the bridging member.

Referring to the drawings, an insulator rack constructed in accordance with the invention, is illustrated as comprising a plurality of vertically extending base members 1 of channel construction arranged in parallel and spaced relation with respect to each other. Each of the base members 1 is provided with a plurality of apertures 2 for the reception of the usual supporting lag screws, not shown.

The base members 1 are further provided with a plurality of equally spaced apertures 3 of substantially T-shape, and having a relatively narrow portion 4 and a comparatively wide transverse portion 5. The wide portions 5 of the apertures are formed by striking up the metal of the base member 1 to form a lip 6, the purpose of which will be hereinafter described.

A plurality of horizontally extending insulator supporting arms or brackets 7, indicated as a whole by the numeral 7, connect the base members 1 and are disposed in superposed relation with respect to each other thereon. The arms 7 are provided with apertures 8 through which the usual insulator re-

taining bolt is adapted to extend. The arms 7 are each preferably pressed from sheet metal and comprise a horizontally disposed insulator supporting portion 9, the opposite 5 sides of which are bent to form downwardly extending flanges 10. The flanges 10 are each provided with a tenon or tongue portion 11 formed with a head 12 and a relatively narrow neck portion 13.

10 In assembling the device, the arms or brackets 7 are arranged in position on the base members 1 by first inserting the tongue portions 11 in the enlarged portions of the apertures 3 formed in the base members 1. 15 The base members are then moved apart a distance sufficient to cause the relatively narrow neck portions 13 of the tongues 11 to enter the narrow portions 4 of the apertures 3. When the various elements of the rack are 20 in this position, the enlarged heads 12 of the tongue portions 11 will prevent the displacement of the arms or brackets 7 from the base members 1 in an outward direction.

The lip portions 6 are then bent downward- 25 ly into the enlarged portions 5 of the apertures 3, from which they were initially struck, completely closing the same, thereby preventing any lateral movement of the members 1 and securely locking the tongue portion 11 in the apertures 3.

It will be readily appreciated, from the foregoing, that by this construction the insulator brackets may be quickly assembled on the base members without the necessity of 35 separately riveting each of the tongues in their respective apertures, as it is a very simple operation to bend down the lip portions 6 to secure the tongue portions in position. The bending of the various lips may be auto- 40 matically accomplished simultaneously by means of a suitable press and the assembly of the parts thereby greatly simplified.

In order that an insulator rack of the type above described may be secured to a supporting structure without the necessity of first removing the insulators, there is provided a bridging member, indicated as a whole by the numeral 14, which is adapted to extend transversely across the rack for engagement 45 with the outer faces of the member 1. The member 14 is preferably formed from material of channel construction having a base portion 15 and flanges 16 and 17. A centrally disposed aperture 18 is provided in the base portion 15 through which a bolt 19 ex- 50 tends to secure the rack to a supporting structure.

In order to prevent the member 14 from 60 turning on the bolt and becoming disengaged from the members 1, in the event that the bolt 19 should become loose, one of the flanges 16 of the member 14 is cut away to provide lugs 20 adjacent to each end thereof which are adapted to register with and project into two 65 of the oppositely disposed lag screw apertures

2 of the base members 1. The other flange 17 is also cut away as indicated at 21 to permit the base portion 15 of the member 14 to lie flat against the members 1 when in position. The central portion of the flanges 16 and 17 70 remaining, are of a length corresponding to the distance between the base members 1 and project therebetween.

When it is desired to secure an insulator rack of the type described, to a pole or other 75 supporting structure the bolt 19 is first disposed in an aperture formed therein with the member 14 loosely mounted thereon. The member 14 is then turned on the bolt 19 to a position parallel to and registering with the 80 elongated opening or space between the base members 1 of the rack. The rack is then disposed in position against the supporting structure and the member 14 turned on the bolt 19 to a substantially horizontal position. 85

If the insulator arms or brackets are disposed relatively close together, which may occur when small insulators are employed, the member 14 may be tilted or moved angularly a slight degree with respect to the supporting structure in order to provide clearance between the adjacent arms. After the member 14 has been moved to its horizontal position, the rack is adjusted vertically until two of the apertures 2 in the base members 1 90 register with the lugs 20 of the bridging member 14. The bolt 19 is then tightened and the base members 1 securely gripped between the member 14 and the supporting structure with the lugs 20 projecting into the apertures 2. 95

From an inspection of Fig. 8 of the drawings, it will be noted that when the lugs 20 are in engagement with the apertures 2, the lower edge thereof is practically in engagement with one of the insulator arms and further prevents any tendency of the bridging member to turn or twist about the bolt 19. By this construction, it will be practically impossible for the bridging member to turn on the bolt 19 and become disengaged from the 100 base members 1 of the rack unless the bolt becomes very loose.

From the foregoing it will be apparent that a very strong and rugged insulator rack is provided that is not only simple in construction and assembly but one that may be quickly and easily secured in position without the inconvenience, heretofore encountered, of first removing the insulators from the rack. 110

What I claim is:

1. A secondary rack having spaced base members, insulator supporting arms connecting said base members so as to provide a unitary structure, a fastening member of elongated shape adapted to pass through the space between said members when positioned longitudinally thereof and to engage the fronts of said base members when turned at right angles to said position and means for 125

mounting said fastening member on a support.

2. A secondary rack having spaced base members, insulator supporting arms associated with said members, means on each arm for separately engaging and securing the spaced base members to the arm so as to provide a unitary structure, a fastening member of elongated shape adapted to pass through 10 the space between said members, when positioned longitudinally thereof and to engage the fronts of said members when turned at right angles to said position and means for mounting said fastening member on a support.

3. A secondary rack having spaced members provided with lag screw receiving openings, insulator supporting arms connecting said base members so as to provide a unitary 20 structure, a fastening member of elongated shape adapted to pass through the space between said members when positioned longitudinally thereof, lugs on said fastening member for engaging said openings in said 25 base members when turned at right angles to said position and means for mounting said fastening member on a support.

4. A secondary rack having spaced base members provided with lag screw receiving 30 openings, insulator supporting arms associated with said members, means on each arm for separately engaging and securing the arm to the spaced base members so as to provide a unitary structure having a longitudinally 35 extending slot of substantial width between said members, a fastening member of elongated shape adapted to pass through said slot when positioned longitudinally thereof and to engage the fronts of said members when 40 turned at right angles to said position, lugs adjacent the ends of said fastening member adapted to be positioned in said openings, flanges on said member adapted to be positioned in said slot when said lugs engage 45 said openings and means for mounting said fastening member on a support.

5. A secondary rack having a base provided 50 with an elongated opening, insulator supporting arms mounted on said base so as to provide a unitary structure, a fastening member

of elongated shape adapted to pass through said elongated opening when positioned longitudinally thereof and to engage said base when turned at right angles to said position, and means for mounting said fastening member on a support.

6. A secondary rack consisting of a unitary frame having a longitudinally elongated opening and carrying an insulator bracket adapted to support the insulator in front of 60 said elongated opening, a fastening means for said frame embodying a headed bolt adapted to be mounted in a support, and a clamping bar mounted rotatably on said bolt between the frame and said insulator and 65 having an elongated shape adapting it to pass through said elongated opening when positioned longitudinally of said frame and to extend across said opening when turned at right angles to said position, whereby when 70 said bolt is tightened said clamping bar will be forced against the face of said frame in contact therewith at opposite sides of said elongated opening.

7. A secondary rack consisting of a unitary frame having a longitudinally elongated opening and carrying an insulator bracket adapted to support the insulator in front of said elongated opening, a fastening means for said frame embodying a headed bolt adapted 80 to be mounted in a support, a clamping bar mounted rotatably on said bolt between the frame and said insulator and having an elongated shape adapting it to pass through said elongated opening when positioned longitudinally of said frame and to extend across 85 said opening when turned at right angles to said position, whereby when said bolt is tightened said clamping bar will be forced against the face of said frame in contact therewith at opposite sides of said elongated opening, and interlocking means between said clamping bar and said frame adapted to come into interlocking relation and hold said clamping bar against rotation on the bolt 90 when said bolt is tightened.

In testimony whereof, I have hereunto subscribed my name this 25th day of May, 1922.

CHARLES L. PEIRCE, Jr.
